UNITED STATES PATENT OFFICE.

WESLEY W. BARNES, OF NEW YORK, N. Y., ASSIGNOR TO STIRN & LYON, OF SAME PLACE.

TOY OR DOLL HOUSE.

SPECIFICATION forming part of Letters Patent No. 256,191, dated April 11, 1882.

Application filed January 26, 1882. (No model.)

To all whom it may concern:

Be it known that I, WESLEY W. BARNES, of the city, county, and State of New York, a citizen of the United States, have invented 5 certain Improvements in Toy or Doll Houses, of which the following is a specification.

My invention relates to toy houses, stables, barns, &c., which are made from detachable pieces or elements, and capable of being taken 10 apart piece by piece and placed in a packing-box, the body of the box serving as a basement for the house, and the sliding cover of the box, in some cases, for the roof. The elements of the house are connected together 15 movably and detachably by means of pins and grooves, so that a child may readily set up the house and dismantle it, and when set up it will be firm and strong. I may apply the same principles of construction to "doll-houses," so 20 called, stables, barns, menageries, &c., the latter containing ordinary toy horses, vehicles, and animals. These latter I do not claim. My invention relates to the manner of constructing 25 the house or inclosure.

25 In the drawings, which serve to illustrate my invention, Figure 1 is a front, and Fig. 2 an end, elevation of a miniature or toy house constructed according to my invention. Fig. 3 is a horizontal sectional plan of the house on 30 the line 3 3 in Figs. 1 and 2. Figs. 4 and 5 are detached details of the same, which will be more particularly referred to hereinafter. Figs. 6, 7, 8, and 9 serve to illustrate modified constructions of my invention, which will be 35 referred to more particularly hereinafter.

Referring to Figs. 1 to 5 most particularly, A is a rectangular box, which serves as a receptacle for the elements of the house, and also for a basement for the same when the 40 house is set up. To serve as a basement the box is turned bottom up, and the cover B (which slides in grooves in the sides of the box when it serves as a cover) is removed.

In the bottom of the box are bored, near its 45 margins, six holes, and into these holes are inserted the round pins or tenons a a on the corner-posts C and intermediate posts, C', of the house. The corner-posts are each provided with two longitudinal grooves in adjacent sides 50 or faces, as shown in Fig. 3, and the intermediate posts each with two grooves on opposite

faces. The panels D D, which form the front of the house, the panels D', which form the ends of the house, and the plain panels D², which form the back of the house, are slipped 55 down in the grooves in the posts, as shown. The box-cover B, which also has six holes bored in it, is now fitted onto the tops of the posts to form a roof, the pins a' on the upper ends of same passing through the holes in said 60 cover. This binds all firmly together. Before putting on the roof B a second floor, consisting of a thin board, E, Fig. 3, may be laid in, its ends resting on cleats b on the end panels, D'. 65

The cornice of the house is constructed of two grooved strips, F, (made in two parts, to get it into the box,) which are attached by forcing the edge of the roof B into the grooves in said strips. In these strips are bored holes to 70 receive tenon-pins on short posts c c, each of which has a groove in its face to receive the ends of a frontispiece, G.

The doors and windows d d in the front and ends of the house are formed by cutting out 75 suitably-shaped parts from the panels and hinging them to the same by means of cloth or leather hinges e, glued or pasted to the parts, as best shown in Fig. 3.

A balcony is formed across the front of the 80 house as follows: Pins f f are inserted in holes in the fronts of the corner-posts C, and on these are slipped an ornamented strip, g, which has a hole bored at each end. Another strip, h, is simply laid on the pins, to serve as a floor, and 85 ornaments i, which may be considered as lamps, are slipped over the ends of the pins, either inside or outside of strip g, they being bored for the purpose, as shown. Another and shorter balcony is arranged below the lower front windows, constructed in the same manner. 90

The steps before the door in the front of the building are constructed as follows: In the side of the box A, forming the basement, are bored two holes at the proper distance apart 95 to suit the length of the steps. Two horses, H H, (seen in side view in Fig. 2 and detached in Fig. 4,) are properly cut from a board and notched to form the risers. These horses have each a pin or dowel, i', which, when the steps 100 are set up, are forced into the holes in the sides of the box. The rear edges of the treads

j are forced into recesses *k*, cut into the horses, as shown. The upper step or platform, *j'*, is simply laid on the horses.

On the exterior of the panels, basement, &c., 5 of the house may be stenciled lines to indicate the bricks, ornamental work, &c., of the house. I have omitted these to avoid obscuring the drawings.

This house may be taken to pieces and put 10 in the box and the roof *B* slipped in to form the box-cover. The pieces that fit into the grooves are made to fit tightly, and the tenon-pins are also made to fit snugly into their sockets.

15 Fig. 5 is a sectional view of the inverted box, showing the position of the groove *l*, in which the cover *B* slides. In Figs. 6 and 7 I have shown my mode of constructing the house as applied to a stable with an open front and 20 pitched roof. Fig. 6 is a front view, and Fig. 7 a vertical section on line 7 7 in Fig. 6. In this construction the ends *D'* are cut to a point or pitched, and the tops of the posts *C C'* are beveled to correspond. The roof is formed of 25 thin boards *B'*, and the cover *B* of the box is utilized to form a sloping approach up to the floor of the stable.

30 *F* is a grooved ridge-pole, in which the edges of the roof-boards are inserted. The left-hand end forms a wagon-house, in which may be put a toy wagon, *I*, and the right-hand end is divided into stalls for toy horses *J J*. The stalls are divided by sloping partitions *m*, the front ends of which slip down in grooves in 35 posts *n*, doweled into the bottom of the box *A*, and the rear ends rest against the back panels, *D²*. A thin board, *p*, forms the front of the feed-box, and is notched into the partitions *m*, and another thin board, *q*, forms the bottom of 40 same. The feed-box extends across all of the stalls.

45 Figs. 8 and 9 show my invention as applied to a toy menagerie. The first is a front elevation, and the latter a section on line 9 9 in Fig. 8. In this construction all the parts, animals, &c., may be packed in the box *A*, and the cover *B* slipped in to close it, as usual. The box is set up on its side to form a basement, and the posts *C³*, which have pins or dowels *a a* in 50 their ends, are fixed in holes in the box, as described in Fig. 1. The short posts *C⁴* have holes in their tops, which receive the projecting ends of the dowels *a*. The frontispieces *G'* are set in grooves in posts *c'* and *C³*, as in 55 Fig. 1, and floors *E'* and roof *B²* are arranged in substantially the same manner as those elements in Fig. 1. The cover *B* serves as a back for the second story, being supported on pins, and slender strips *r r* run through holes in the 60 sides of the box and the floors and roof to form imitation bars.

65 I am aware that toy houses have been constructed with grooved corner-posts and panels arranged to slide into them, the posts being kept in place by means of halved sills and caps

secured by pins in the ends of the posts; and I am also aware that such houses have been built up of pieces somewhat in the manner of a log-house and merely set on the box which is intended to contain the parts; but I am not 70 aware of the box having ever been constructed to serve as a part of and basement for the house, or the cover of the box having been constructed to serve as a flat roof for the house, or of the doors and windows of the house having been 75 constructed as I have herein described.

Having thus described my invention, I claim—

1. The sides of a toy house, constructed of panels arranged to slide in grooves in the posts, 80 as shown, and provided with doors and windows cut in the said panels, and the pieces *d* cut therefrom provided with flexible hinges *e*, and hinged to said panels at the margins of the openings, substantially as shown. 85

2. The combination of the box having holes or sockets in its bottom to receive the tenons on the posts, the grooved posts with tenon-pins on their ends, the cover of the box having holes or sockets to receive the tenons on the 90 upper ends of the posts, and the panels arranged to slide into the grooves in the posts, and provided with windows and doors cut from them and hinged substantially as shown, all arranged substantially as set forth. 95

3. The cornice of a toy house, constructed of the grooved pieces *F*, posts *c*, and frontispiece *G*, in combination with the roof *B*, all arranged substantially as set forth. 100

4. The combination, with a toy house, of the balcony constructed of the pins *f*, floor *h*, and ornamented with strip *g*, all arranged substantially as set forth. 105

5. The combination, with a toy house, of the steps, comprising the horses *H*, provided with pins *i* and recesses *k*, and the steps *j*, all arranged substantially as set forth. 110

6. The combination, with the elements of the superstructure of a toy house—namely, the tenoned and grooved posts, and the panels—of the box *A*, constructed to serve as a basement for the same, and the cover *B*, constructed to serve as a roof for the same, substantially as set forth. 115

7. The combination, to form a toy house, of the inverted box *A*, provided with holes in its bottom to receive the tenons on the posts, and holes in its side to receive the pins on the horses of the steps, of the tenoned and grooved posts *C C'*, the box-cover *B*, the panels *D D' D²*, the cornice, the balcony, and the steps, all constructed substantially as set forth. 120

In witness whereof I have hereunto signed my name in the presence of two subscribing witnesses.

WESLEY W. BARNES.
